BATHLIFT FOR INVALIDS AND CONVALESCENTS

Viola J. Reimold and Ward J. Blunt, Saginaw, Mich.,
assignors to National Sales Co., Saginaw, Mich.

Filed May 21, 1964, Ser. No. 80,098

Term of patent 7 years

(Cl. D83—1)

Fig. 2

Fig. 1

FIG. 1 is a perspective view of the bathlift for invalids and convalescents.

FIG. 2 is a top plan view thereof.

The undisclosed side of the gear housing box is the same as the side shown and the rear portion is flat and plain.

We claim:

The ornamental design for a bathlift for invalids and convalescents, as shown and described.
